Attorney

UNITED STATES PATENT OFFICE.

JOHN ERICKSON, OF CHICAGO, ILLINOIS, ASSIGNOR TO AUTOMATIC ELECTRIC COMPANY,
OF CHICAGO, ILLINOIS, A CORPORATION OF ILLINOIS.

MEASURED-SERVICE TELEPHONE SYSTEM.

1,316,704.

Specification of Letters Patent. Patented Sept. 23, 1919.

Application filed December 24, 1917. Serial No. 208,654.

To all whom it may concern:

Be it known that I, JOHN ERICKSON, a citizen of the United States of America, and a resident of Chicago, Cook county, and State of Illinois, have invented certain new and useful Improvements in Measured-Service Telephone Systems, of which the following is a specification.

My invention relates in general to measured service systems and particularly to meter control circuits for use in automatic telephone systems.

More specifically my invention provides an improved metering arrangement which is especially adapted to be placed at a subscriber's substation either on a single or polystation line, and which involves certain novel and highly useful features which will be pointed out and described hereinafter.

My invention in this application is somewhat similar to that shown in my prior application Serial No. 181,727, filed July 20, 1917, the apparatus and circuits differing therefrom in certain details and methods of operation as will be pointed out.

Referring to the drawing, I have shown a substation in preferred form, together with a fragmentary showing of certain exchange circuits to more clearly show the operation of the meter at said substation.

More in detail a complete substation A is shown at the left of the figure, the wipers only of a line or selector switch are shown at C, while only the essential parts of a connector switch are shown at D, namely, the line and back bridge relays and the wipers, a subscriber's line is shown accessible to the connector switch D and a substation B is shown connected thereto. A meter M is associated with the substation A.

The substation A may be of any well known common battery type and comprises the usual receiver 2, transmitter 3, switch hook 4, ringer 5, and condenser 6. Being an automatic substation there is also provided a calling device or impulse sender C. D. of which only the impulse springs 7 and 8 and the shunt springs 9 and 10 are shown. This calling device may be of the type in which the impulse springs are controlled through the medium of a finger hole dial to produce series of interruptions in the line circuit in accordance with the digits of the

called number. Reference being had to the British patent to Dicker, No. 29,654 of 1910.

The meter M associated with the substation A comprises a polarized controlling relay 11, and a push button 12, which controls the arm 13 and its upright arm 14 to prepare the meter for operation and operates the springs 15—18 inclusive. The meter may be of any ordinary form, comprising a series of number wheels, which are adapted to register the total number of calls. The functions of the various elements will be fully explained hereinafter.

The two line conductors 19 and 20 extend from the substation A to the exchange where they terminate in the wipers of an individual switch C of which only the two lines wipers are shown. For the sake of simplicity, I have shown the line switch C as having direct access to connector switches D, although it will be understood that selector switches of the usual type may be interposed according to the size of the exchange. The connector D, may also be of any approved type, its most essential characteristic being the provision of means whereby, upon the response of a called subscriber, the incoming line conductors are reversed as regards their connection with the windings of the line relay to thereby reverse the direction of the current flow in the calling line. Thus the line conductors 19 and 20 before terminating in the windings of the line relay 21, pass through the reversing springs of a back bridge relay 22. Switches of suitable construction may be found in U. S. Letters Patent to Newforth, Reissue No. 13,901. The substation A is one of the several stations on a polystation line and it will be understood therefore that in addition to the substation A a number of other substations may be connected in bridge of the line conductors 19 and 20.

Having given a brief description of the apparatus involved, I will now explain in detail the mode of operation. The subscriber at A desiring to establish a connection with the subscriber at substation B, first presses the button 12 and then removes his receiver, thereby closing the line circuit through the switch hook springs 28 and 27. As the line of substation A is a party line, it is important that the subscriber be first

allowed to listen in by simply removing his receiver without giving his meter a chance to operate because of an answered call having been set up by another subscriber 5 on the same line.

By pressing the button 12, a high resistance 24 is included in the line circuit by the separation of the springs 15 and 16, which are operated by the bushing 26. When the 10 receiver is now removed, the listen in circuit may be traced from the line conductor 19, switch hook springs 28 and 27, receiver 2, transmitter 3, polarized relay 11 and non-inductive resistance 23 in parallel, resistance 15 24 and springs 7 and 8 to the line conductor 20. The resistance 24 may be of such high resistance (5000 ohms or more) that the current flowing in the line circuit at this time will not be strong enough to operate the 20 polarized relay 11. At the time the button 12 was depressed to listen in, the arm 13 and its associated arm 14 were pressed to the right, at the limit of its motion, three results occur, namely, the right hand end 25 of the arm 13 falls behind the next tooth of the ratchet wheel 30, the springs 17 and 18 are opened and the upper end of the arm 14 falls behind the tooth on the under side of the armature 25. As soon as the arm 14 locks 30 behind the armature 25, the arm 13 passes out of operative engagement with the push button 12, so that the subscriber cannot by holding the button depressed prevent the operation of the number wheels. The separation 35 of the springs 17 and 18 removes the short circuit which normally existed about the calling device springs 7 and 8. Should the calling subscriber find that another conversation is taking place at this time, he will 40 first hang up his receiver and then restore the button 12 to normal. The restoration of the button 12 simply closes the shunt circuit about the resistance 24, and leaves the arms 13 and 14 in their advanced position.

45 Should the subscriber have found the line idle, he would simply restore the button 12 to short circuit the resistance 24. The short circuiting of the resistance 24 at this time, causes the usual operation of the line switch 50 C to extend the line conductors 19 and 20 to an idle connector switch D. The circuit for operating the line switch may be traced from the line conductor 19 through the springs 28 and 27, receiver 2, transmitter 55 3, polarized relay 11 and non-inductive resistance 23 in parallel, springs 15 and 16, springs 8 and 7 of the calling device C. D. to the line conductor 20. A circuit will now be closed from battery through the upper 60 winding of the line relay 21 of the connector D over the above traced circuit through the substation A and back over the other side of the line and through the lower winding of the relay 21 to ground. The current in 65 this circuit is of such a direction as to main-

tain the armature 25 of the polarized relay 11 attracted to the lower pole piece of the said polarized relay, thereby maintaining the meter operating arms 14 and 13 locked in their advanced position. The subscriber 70 at A will now operate his calling device C. D. and by separating the springs 7 and 8 a predetermined number of times will operate the connector switch D to connect with the line leading to the substation B, whereupon 75 said line is tested automatically and if idle, is automatically signaled through the medium of the usual automatic ringing equipment of such a connector and the ringer 80 31 at substation B. During the operation of the calling device C. D. the springs 9 and 10 are maintained in contact, thereby short circuiting the polarized relay 11, the transmitter 3, and the receiver 2, in order to prevent annoyance to the subscriber, caused by 85 the interruptions of the line circuit. The subscriber at substation B upon hearing the signal, removes his receiver to answer the call, at which time a circuit is closed for the back bridge relay 22, which extends from 90 battery through the upper winding of said relay to and through the transmitter and receiver of the substation B and back over the other side of the line and through the lower winding of said relay to ground. The relay 95 22 energizes over this circuit and operates to reverse the connections of the line relay 21 with regard to the line conductors 19 and 20, thereby reversing the direction of the current flow over said line conductors and through 100 the talking equipment of the substation A and the polarized relay 11 in series. This reversal of current through the polarized relay 11 causes the arm 25 to be attracted toward the upper pole of said relay. This operation 105 of the relay 11, unlocks the arms 14 and 13 and allows said arms to be returned to their normal position through the medium of the spring 32. The retracting movement of the arm 13 causes the ratchet wheel 30 to be advanced one step and again closes the contact 110 of the springs 17 and 18. The wheel 30 operates the well known number wheels of the meter to register the call, and the springs 17 and 18 again restore the short circuit 115 about the springs of the calling device C. D. The subscribers may now carry on the conversation over the heavy conductors, and when the conversation is completed, the subscriber at substation A releases all the apparatus to normal by hanging up his receiver 2 and thereby opening the line circuit 120 at the springs 28 and 27.

125 It will be seen therefore, that I have provided a very simple and highly efficient meter arrangement for use with polystation lines in which the subscriber must first depress a push button in order to include a high resistance which will prevent a false operation of his meter in case the line is 130

already in use; and also to render his calling device operative by removing a short circuit therefrom. Means has also been provided for preventing a subscriber from holding the push button depressed in order to prevent the proper operation of his meter, that is, the meter operating arm 13 passes out from under the control of the push button as soon as the button has been pressed and also the push button must be released in order to remove the short circuit from the high resistance 24 before the switches can be operated to set up a connection.

Having described my invention, what I consider to be new and desire to have protected by Letters Patent will be pointed out in the appended claims.

What I claim as my invention is:

1. In a telephone substation, the combination with talking equipment and suitable circuits therefor, of a meter, mechanical means for operating said meter normally inoperative to operate said meter, a push button for bringing said means into operative engagement with said meter, a magnet for controlling said means to operate said meter, means whereby a subscriber may extend a connection from said substation to a called line, means for preventing a subscriber from extending a connection until said push button is operated, the operation of said magnet controlled by the called subscriber.

2. In a telephone substation, the combination with talking equipment and suitable circuits therefor, of a meter, mechanical means for operating said meter normally inoperative to operate said meter, a push button for bringing said means into operative engagement with said meter, a magnet for controlling said means to operate said meter, means for extending a connection from said substation to a called line, means for preventing a subscriber from extending a connection unless said push button is operated, and means controlled by the called subscriber for operating said magnet to operate said means.

3. In a telephone substation, the combination with talking equipment and suitable circuits therefor, of a meter, mechanical means for operating said meter normally inoperative to operate said meter, a push button for bringing said means into operative engagement with said meter, a magnet for controlling said means to operate said meter, means whereby a subscriber may extend a connection from said substation to a called line, means for preventing a subscriber from extending a connection until said push button is operated, and means controlled by the called subscriber for operating said magnet to operate said means to thereby operate said meter to register the call.

4. In a telephone system, the combination with talking equipment and suitable circuits therefor, of a meter, mechanical means

for operating said meter normally in operative to operate said meter, a push button for bringing said means into operative engagement with said meter, a magnet for controlling said means to operate the meter, means for extending a connection from said substation to a called line, means for preventing a subscriber from operating said last means to extend a connection until said push button is operated, and means for thereafter operating said magnet to operate said means.

5. In a telephone system, the combination with talking equipment and suitable circuits therefor, of a meter, mechanical means for operating said meter normally inoperative to operate said meter, a push button for bringing said means into operative engagement with said meter, a magnet for controlling said means to operate the meter, means for extending a connection from said substation to a called line, means for preventing a subscriber from operating said last means to extend a connection until said push button is operated, and means controlled by the called subscriber for thereafter operating said magnet to operate said means.

6. In a telephone system, the combination with talking equipment and suitable circuits therefor, of a meter, mechanical means for operating said meter normally inoperative to operate said meter, a push button for bringing said means into operative engagement with said meter, a magnet for controlling said means to operate the meter, means for extending a connection from said substation to a called line, means for preventing a subscriber from operating said last means to extend a connection until said push button is operated, and means for thereafter operating said magnet to operate said means to thereby operate said meter to register the call.

7. In a telephone substation, talking equipment and suitable circuits therefor, a meter for said substation, a calling device for said substation normally inoperative, a mechanical device for operating said meter normally inoperative to operate said meter, a push button for bringing said mechanical device into operative engagement with said meter and for rendering said calling device operative, a magnet for holding said mechanical device in operative relation to said device, and means for operating said magnet to release said mechanical device to operate said meter.

8. In a telephone substation, talking equipment and suitable circuits therefor, a meter for said substation, a calling device for said substation normally short circuited, a mechanical device for operating said meter normally inoperative to operate said meter, a normally short circuited resistance for rendering said substation inoperative for all operations except listening in, a push button,

- means whereby when said button is pressed the mechanical device is brought into operative relation with said meter, and the short circuits are removed from said calling device and resistance, and whereby when said button is released, the short circuit is restored about said resistance, and means for controlling said mechanical device to operate said meter.
- 10 9. In a telephone substation, talking equipment and suitable circuits therefor, a meter for said substation, a calling device for said station normally short circuited, a mechanical device for operating said meter normally inoperative to operate said meter, a normally short circuited resistance for rendering said substation inoperative for all operations except listening in, a push button, means whereby when said button is pressed the mechanical device is brought into operative relation with said meter, and the short circuits are removed from said calling device and resistance, and whereby when said button is released, the short circuit is restored about said resistance, a magnet for maintaining said mechanical device in operative relation with said meter, and means controlled by the called subscriber for operating said magnet to release said mechanism to operate said meter.
- 15 10. In a telephone substation, talking equipment and suitable circuits therefor, a meter for said substation, a calling device for said substation normally inoperative, a mechanical device for operating said meter normally inoperative to operate said meter, a push button for bringing said mechanical device into operative engagement with said meter and for rendering said calling device operative, a polarized magnet for holding said mechanical device in operative relation to said device, and means for reversing the current in said magnet to release said mechanical device to operate said meter.
- 20 11. In a telephone substation, talking equipment and suitable circuits therefor, a meter for said substation, a calling device for said station normally short circuited, means controlled by said device for extending a connection from said substation to a
- 25 30 35

called subscriber, a mechanical device for operating said meter normally inoperative to operate said meter, a normally short circuited resistance for rendering said substation inoperative for all operations except listening in, a push button, means whereby when said button is pressed the mechanical device is brought into operative relation with said meter, and the short circuits are removed from said calling device and resistance, and whereby when said button is released, the short circuit is restored about said resistance, a magnet for maintaining said mechanical device in operative relation with said meter, and means controlled by the called subscriber for operating said magnet to release said mechanism to operate said meter.

11. In a telephone substation, talking equipment and suitable circuits therefor, a meter for said substation, a calling device for said substation normally inoperative, a mechanical device for operating said meter normally inoperative to operate said meter, a push button for bringing said mechanical device into operative engagement with said meter and for rendering said calling device operative, a polarized magnet for holding said mechanical device in operative relation to said device, and means for reversing the current in said magnet to release said mechanical device to operate said meter.

Signed by me at Chicago, Cook county, Illinois, this 17th day of December, 1917.

JOHN ERICKSON.
